UNITED STATES PATENT OFFICE.

TORIS N. JOHNSEN, OF WILBUR, WASHINGTON.

WAGON-BRAKE.

No. 820,875.

Specification of Letters Patent.

Patented May 15, 1906.

Application filed June 2, 1905. Serial No. 263,400.

To all whom it may concern:

Be it known that I, TORIS N. JOHNSEN, a citizen of the United States, and a resident of Wilbur, in the county of Lincoln and State 5 of Washington, have made certain new and useful Improvements in Wagon-Brakes, of which the following is a specification.

My invention is an improvement in automatic wagon-brakes; and it consists in certain novel constructions and combinations of parts hereinafter described and claimed.

Referring to the drawings forming a part hereof, Figure 1 is a side elevation with the near wheels removed. Fig. 2 is a bottom 15 plan view. Fig. 3 is a detail section on the line 3-3 of Fig. 1. Fig. 4 is a detail section of the roller-bearing.

In the practical application of my invention I provide a wagon comprising front and 20 rear axles A A', having the hounds C C' and connected by the coupling-pole B.

The bolsters D are secured to the front and rear axles in the ordinary manner, and standards d, having the form shown in Fig. 4, are 25 secured to the ends of the bolsters. The standards are the same in construction, and a description of one will suffice for all. Each standard d is formed of a plate having the perforations d⁰ and the opening d', and in the 30 latter is journaled the roller d² with its axis perpendicular to the bolster.

In the lower perforations d⁰ of the opposite standards is journaled a roller d³ longitudinally of the bolster, upon which rests the 35 wagon-body E, the sides thereof being engaged by the perpendicular rollers d². This construction of bed-support is used in wagons of heavy draft; but in those of lighter draft I provide a spring d³, journaled beneath the 40 wagon-bed and having its outer ends bent upwardly and outwardly to engage the upper perforation d⁰ in the standards, two springs being provided at each end of the bed.

45 Brackets e are secured to the wagon-bed adjacent to the rear wheels, and secured to the coupling-pole and rear hounds is a cross-bar e', provided at either end with the transverse bolts e², having upper and lower eyes 50 e³ e⁴. To the upper eyes are attached the yokes e⁵, having journaled in the arms thereof the rollers e⁶, engaging the brackets e, and to the lower eyes e⁴ are attached links e⁷.

A brake-beam e⁸, provided with the eye-bolts e⁷, engaging the links e⁶ on the bolts e², depends therefrom below the coupling-pole 55

and is provided at either end with the brake-shoes e⁹.

A rock-shaft e¹¹ is journaled in bars e¹⁰ on the rear axle and is provided at its outer ends with upwardly-extending arms e¹⁴, engaging quadrant-shaped brackets e¹², provided with the transverse perforations e¹³. An arm e¹⁵, depending from the rock-shaft e¹¹, is connected by a rod e¹⁶ to the brake-beam. 65

The operation of my improvement is entirely automatic. When moving on level ground, the relation of the parts is unchanged; but on starting down an incline the bed tends to swing forward when spring-supported or to 70 roll forward when on the rollers, rocking the rock-shaft and drawing the brake-beam to the rear, thus pressing the shoes against the peripheries of the wheels. As soon as level ground is reached the bed swings or rolls 75 back, rocking the rock-shaft in the reverse direction, releasing the brake-shoes.

The power of the brake may be regulated by pushing the upwardly-extending arms of the rock-shaft forward and securing them in 80 their adjusted position by a pin through the perforations.

The provision of the rollers in the standards removes all friction between the bed and the standard and also provides an efficient 85 support against outward pressure.

By swinging the brake-beam from the bed I prevent downward strain on the coupling-pole, while at the same time the cross-bar retains the brake-beam in fixed parallel relation with the rear axle. 90

To prevent undue motion rearward of the bed, the rear edges of the standards are provided with inward projections d⁴, which engage the upwardly-extending arms of the 95 spring.

It will be evident from the description that I provide a brake simple in construction, reliable, efficient, and entirely automatic in its action. 100

The wagon is easily detached from the brake-beam when the said bed is removed from the wagon, and the brake is left upon the running-gear and may then be operated by hand in the usual manner. 105

Having thus described my invention, what I claim as new, and desire to secure by Letters Patent, is—

1. In a wagon-brake, the combination of the front and rear axles, the coupling-pole, bolsters supported on the axles, standards on the bolsters, rollers journaled in the stand-

- ards longitudinally of the bolsters, rollers journaled in the individual standards longitudinally thereof, a wagon-bed supported by the rollers, brackets on the bed, a cross-bar 5 secured to the coupling-pole, bolts traversing the ends of the cross-bar, and provided with upper and lower eyes, yokes engaging the upper eyes, rollers journaled in the arms of yokes and engaging the brackets, eyebolts 10 engaging the lower eyes, a brake-beam secured to the eyebolts, brake-shoes on the ends of the brake-beam, bearings on the rear axle, a rock-shaft journaled in the bearings, brackets on the sides of the bed and provided with 15 perforations, upwardly-extending arms on the ends of the rock-shaft for engaging the brackets, a central depending arm on the rock-shaft, and a rod connecting the depending arm with the brake-beam.
- 20 2. In a wagon-brake, the combination with the bed of a front and rear axle, the coupling-pole, bolsters supported on the axles, standards on the bolsters, rollers journaled in the standards longitudinally thereof, means connected with the standards for supporting the 25 wagon-bed, a brake-beam depending from the bed, means for maintaining the brake-
- beam in fixed relation with respect to the coupling-pole, brake-shoes on the ends of the brake-beam, a rock-shaft journaled in the rear axles, brackets having a plurality of perforations secured to the bed, arms on the rock-shaft for engaging the brackets, whereby the longitudinal movement of the bed may rock the shaft, and a connection between the 30 rock-shaft and the brake-beam whereby the rocking of the shaft may operate the brake. 35
3. In a wagon-brake, the combination of a front and a rear axle, bolsters having standards supported on the axles, a bed supported 40 on the bolsters, means whereby the bed may move longitudinally upon the bolsters, a brake-beam depending from the bed, brake-shoes on the ends of the brake-beam, a rock-shaft journaled on the rear axle, brackets 45 having a plurality of perforations secured to the bed, arms on the rock-shaft for engaging the bracket, and connections between the rock-shaft and the brake-beam whereby the rocking of the shaft may operate the brake. 50
